Primary Examiner — Derrick Holland(74) *Attorney, Agent, or Firm* — Ware, Fressola, Maguire & Barber LLP**(57) CLAIM**

The ornamental design for a metal clad/armored clad electrical cable to electrical enclosure electrical transition fitting housing, as shown and described.

DESCRIPTION

FIG. 1 is a front perspective view of the metal clad/armored clad electrical cable to electrical enclosure electrical transition fitting housing of my design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof; and,

FIG. 8 is a right side view thereof, shown in environmental use.

The broken lines shown represent unclaimed subject matter and form no part of the claimed design.

1 Claim, 5 Drawing Sheets(56)
